UNITED STATES PATENT OFFICE.

ROMAN NELDNER, OF MILWAUKEE, WISCONSIN.

TRANSPOSING DEVICE FOR PLAYER PIANOS.

1,408,824.

Specification of Letters Patent.

Patented Mar. 7, 1922.

Application filed March 29, 1920. Serial No. 369,825.

To all whom it may concern:

Be it known that I, ROMAN NELDNER, a citizen of the United States, and resident of Milwaukee, in the county of Milwaukee and State of Wisconsin, have invented certain new and useful Improvements in Transposing Devices for Player Pianos; and I do hereby declare that the following is a full, clear, and exact description 10 thereof.

My invention relates to certain new and useful improvements in pneumatic player pianos, or the like and refers more particularly to means for transposing the key of 15 a roll being played.

Former devices of this character necessitated the shifting of the tracker bar to change the relation of its ports with respect to the perforations of the music roll, but 20 while this method served to transpose the key, still it has proven more or less objectionable in that the shifting of the tracker bar throws the expression port out of line with the expression slot of the roll and 25 hence renders the expression controlling mechanism inoperative.

Thus the present invention has for its primary object to provide means for transposing the key of a music roll without changing the relation of the expression port with 30 the expression slot of the music roll.

A more specific object of my invention is to provide means for visually indicating the key in which a music roll is being 35 played.

With the above and other objects in view which will appear as the description proceeds, my invention resides in the novel construction, combination and arrangement 40 of parts, substantially as hereinafter described, and more particularly defined by the appended claim, it being understood that such changes in the precise embodiment thereof may be made as come within 45 the scope of the claim.

In the accompanying drawing I have illustrated one complete example of the physical embodiment of my invention constructed according to the best mode I have 50 so far devised for the practical application of the principles thereof, and in which:

Figure 1 is a front plan view of the roll compartment of a pneumatic player equipped with my invention, and

55 Figure 2 is a sectional view taken ver-

tically through the music roll compartment on the line 2—2 of Figure 1.

Referring now more particularly to the accompanying drawing, 1 represents a box or casing forming the music roll compartment and having disposed in its upper part a pair of stub shafts 2 and 3 adapted to journally mount a roller 4 having wound therearound a perforated music roll 5. Journally mounted in the lower portion of 60 the music roll compartment is an operating drum 6 which has its shaft 7 journaled in the walls of the compartment, and intermediate roller 4 and drum 6 is rigidly mounted a tracker bar 8 having perforations therein adapted for engagement with the perforations of the music roll 5. The drum 6 and roller 4 are operated by any desired means which engage stub shaft 3 and the corresponding end of shaft 7, and as 65 this constitutes no important feature of the present invention, the same has not been shown in the accompanying drawing.

As best shown in Figure 2 each port of tracker bar 8 has leading therefrom a duct 9 which is coupled with an operating pneumatic, not shown, and intermediately disposed across the ducts 9 in a slide valve comprising an inner section 10 having a series of ports therein and leading from the ports 80 are tubes 10' adapted to receive the inner ends of that portion of ducts 9 leading from the ports of tracker bar 8, and an outer section 11 having ports therein similar to section 10, and leading from the ports of section 11 are tubes 11' adapted to receive the inner ends of that portion of ducts 9 connected with the pneumatics.

The sections 10 and 11 are each provided with a like central raised portion, the adjacent faces of which are held in air tight engagement, and the peripheral edges of section 11 are directed laterally as at 12 for sliding engagement in a guide slot formed by the peripheral edges 13 of section 10, each of 95 which is directed laterally, and then folded upon itself. Thus by this construction an air tight slide valve is provided, and for operating the same from the front of the player an operating rod 14 is journaled in bearings 100 15 mounted in the roll compartment, and the rear end of rod 14 projects rearwardly of the rear of casing 1 and has secured thereon a crank arm 16 which has its outer free end 17 bifurcated to engage a stud 18 car- 110

ried by the section 11, and the other end of rod 14 has secured thereon an knurled head 19 for operating the same.

As will be obvious, upon rotating rod 14 5 in either direction, the ports of sections 10 and 11 are changed with relation to each other and in this manner, the key of the roll being played is transposed as will be readily understood by those skilled in the art to 10 which an invention of this character appertains, and for visually indicating the key in which the roll is being played, a plate 20 is carried by the outer bearing 15 and has thereon suitable indications with which a 15 pointer 21 formed on knurled head 19 registers.

From the foregoing description taken in connection with the accompanying drawing, it will be readily seen that in transposing 20 the key of a roll being played, the relation of expression port 22 in bar 8 with its controlling slot or perforations 22' in roll 5 will not be changed, as is the case in former devices of this character.

25 I claim:—

In a player piano, a tracker board having

ports therein adapted to co-operate with a perforated music sheet, a bar having transverse openings therethrough which are in communication with the tracker board ports 30 respectively, a second bar having transverse openings adapted to communicate with the primary pneumatics and adapted to register with the openings in the first named bar, one of said bars being slidable with respect to 35 the other to shift the openings therein respectively into registry with the next higher or next lower openings of the other bar whereby to transpose the key of the piece being played, said bars being channel shaped 40 and one fitting over the other, the outer bar having flanges extending outwardly from the sides of the channel and the inner bar having flanges extending outwardly and around the flanges on said outer bar 45 whereby to hold the bars closely together and prevent leakage of air therebetween.

In testimony that I claim the foregoing I have hereunto set my hand at Milwaukee, in the county of Milwaukee, and State of 50 Wisconsin.

ROMAN NELDNER.
